[57] CLAIM

The ornamental design for a stake for plant, as shown and described.

DESCRIPTION

FIG. 1 is an exploded side view of the upper and lower portions of a stake for plant, showing my new design; FIG. 2 is an exploded front elevational view of said upper and lower portions;

FIG. 3 is an exploded rear elevational view of said upper and lower portions;

FIG. 4 is a bottom plan view of the lower portion taken along line IV—IV of FIG. 2;

FIG. 5 is a top plan view of the lower portion taken along line V—V of FIG. 2;

FIG. 6 is a bottom plan view of the upper portion taken along line VI—VI of FIG. 2;

FIG. 7 is a top plan of the upper portion taken along line VII—VII of FIG. 2; and,

FIG. 8 is a perspective view of the claimed design.
